FLICKERLESS OPERATION OF ELECTRIC
LIGHTING ELEMENTS

Lester F. Bird, Newark, N. J.

Application July 23, 1947, Serial No. 762,868

7 Claims. (Cl. 315—239)

1

This invention relates to an improvement in the flickerless operation of electric lighting elements and employs a frequency multiplication system in connection with the operation of such elements, such as fluorescent lamps and neon advertising signs, from standard commercial lighting frequencies.

The principal object of my invention is to secure flicker free light from electric discharge tubes and the like operating on a low frequency alternating current supply line, in an economical and simple manner.

Another object is to provide a single system from which a number of discharge tubes or the like may be so operated.

A further object is to obtain the desired results without the use of expensive parts or parts subject to wear and disorder.

A still further object is to have a system that reduces the effects of supply line voltage fluctuation and produces an output of light substantially free from variations.

It is well known that electric discharge tubes of the types described do not give off light continuously at a uniform intensity but give it off in pulses at twice the frequency of the supply line voltage. Eye strain frequently results from prolonged use of fluorescent lamps operating on a 60 cycle supply line. When the supply line frequency is below 50 cycles per second, the pulsations of light become apparent to the human eye in the form of an annoying flicker, and when only a 40 cycle supply is utilized the flicker becomes so pronounced that a tube of this nature is no longer usable as a reading lamp.

I obtain flicker free light from electric discharge tubes by utilizing certain applications of electrical circuit design by which the frequency of the supply line is multiplied so as to be above the flicker frequency and then use this higher frequency to operate the tubes. For example, the frequency of a 25 cycle supply I may multiply to 75 cycles and when a discharge tube operates on this higher frequency no flicker is apparent to the normal human eye. I do this by employing only fixed electrical components such as transformers, reactors and capacitors which have no moving parts and last indefinitely.

The following is a description of certain circuits embodying my invention, which when read in connection with the following drawings will explain how I obtain the desired results.

In the drawings in which the same number represents the same or a similar part:

Figure 1 is a frequency multiplication circuit

2

with a certain arrangement of electrical components.

Figures 2, 3 and 4 are similar circuits, each modified to some extent by the rearrangement, addition or omission of certain electrical components.

In Figure 1 alternating current supply line leads 12 and 13 are connected to primary coil 2 of a reactance type of transformer 1, sometimes commonly referred to as a high leakage type transformer. Core structure 3 of transformer 1 is designed to provide loose magnetic coupling between primary coil 2 and secondary coil 4 so that the secondary circuit may oscillate without too much reaction back on the primary circuit. It is desirable that there be sufficient leakage reactance between the primary and secondary windings so that the secondary kva. is limited to about 150% of the normal load power of the transformer when the secondary of the transformer is operated under short circuit conditions.

Reactor 5 is shown in the circuit of Figure 1 on secondary line 14 as a separate unit electrically, but actually it is built in as an integral part of transformer 1.

Across the secondary lines 14 and 15 I place capacitor 6 having such a reactance that at the third harmonic frequency of the supply voltage, the inductive reactance of the transformer secondary and the capacitive reactance of the condenser are equal.

Capacitor 6 and the reactance of the secondary of the transformer, therefore, form a resonant system which is resonant to the third harmonic frequency of the supply. In common with all resonant systems, this one will oscillate if it is excited at the proper intervals. The supply frequency in this case produces the necessary excitation giving the resonant system impulses at one-third the oscillating frequency. With the proper design of transformer 1 and capacitor 6 considerable energy will flow in the oscillating system and if not loaded too heavily will deliver usable power. I find that about 6 to 12 kva.'s of energy must flow in the oscillating system for each kilowatt of energy delivered to the load.

Being provided with this increased harmonic frequency the discharge tube 8 can be operated in the usual manner with stabilizing ballast such as reactor 7 designed for the harmonic frequency.

While I have discussed the third harmonic frequency, it is apparent that some other multiple of the original supply line frequency may be similarly developed.

Such a circuit as I have described functions as follows. If the inductance of the secondary coil and core structure has a value of 126 ohms at the supply line frequency and 378 ohms at the third harmonic frequency, the capacitor would then have a reactance of 378 ohms at the harmonic frequency. Because of the loose coupling existing between the primary and secondary coils on the core, the resonant secondary circuit is free to oscillate with but little reaction on the input circuits. That this is exactly the result is clearly shown by the manner in which this circuit reacts when connected to a variable line supply voltage. With low input very little third harmonic appears across the capacitor. As the input is gradually increased the fundamental and third harmonic increase together up to a certain point when there is a jump in the third harmonic voltage and it becomes predominant across the capacitor. Further increase in line voltage results in no further increase in harmonic voltage. In fact, a further increase in input voltage results in a reduction in harmonic voltage although this effect is gradual and this system gives almost constant output of harmonic voltages over 15% or more of line voltage change. This effect is very desirable since it renders the harmonic voltage essentially independent of the input throughout the range of variation ordinarily found in supply line voltages.

The harmonic voltages generated suffer from regulation due to loading and this effect is not especially desired but can be eliminated by the use of the well known regulating circuits, following the harmonic generating circuit so that good regulation is secured under conditions which avoid overloading.

In Figure 2 as well as in Figures 3 and 4 reactor 5 is not shown separately, its function being performed by the reactance built into secondary coil 4 of transformer 1.

In Figures 3 and 4 the tube 8 is shown with auxiliary stabilizing reactance operating from only a portion of the harmonic voltages generated across the capacitor. In Figure 4, single capacitor 11 is placed across secondary lines 15 and 16 and reactor 7 is variably connected to secondary coil 4 of transformer 1 through line 17.

There are other modifications that may be made in the circuits described and other circuits employed that embody my invention, and I do not limit the scope of my invention to the specific forms herein set forth.

What I claim is:

1. An electric circuit connected to a source of alternating current, comprising a high reactance type transformer, a shunt capacitor connected across the secondary coil of such transformer with reactance equal to the reactance of such secondary coil at an harmonic frequency of the supply voltage and an electric discharge tube and a reactance in series with said tube connected to the secondary coil of such transformer.

2. An electric circuit connected to a source of alternating current, comprising a transformer having a primary and a secondary coil with a limited magnetic coupling between them, a shunt capacitor connected across such secondary coil with reactance equal to the reactance of the secondary coil of such transformer at an harmonic frequency of the supply voltage and an electric discharge tube and a reactance in series with said tube connected to the secondary coil of such transformer.

3. A substantially flicker free light producing system comprising a low frequency alternating current power source, a high reactance transformer including in addition to a primary winding a secondary winding mounted upon a magnetic core structure partially in the magnetic field generated by the primary winding and having a substantial inductive reactance, a capacitor with reactance equal to the inductive reactance of said secondary coil at an harmonic frequency of the supply voltage connected across said secondary coil, a light producing element, and a stabilizing unit adapted to operate the light producing element at the harmonic voltage generated in the secondary coil circuit.

4. A frequency multiplying arrangement adapted to be energized by a source of alternating current comprising, in combination, a low frequency alternating power source, a high reactance transformer including in addition to a primary winding a secondary winding mounted upon a magnetic core structure partially in the magnetic field generated by the primary winding and having a substantial inductive reactance, a capacitor with reactance equal to the inductive reactance of said secondary coil at an harmonic frequency of the supply voltage connected across said secondary coil, a light producing element, and a stabilizing unit adapted to operate the light producing element at the harmonic voltage generated in the secondary coil circuit.

5. In a pulsating light producing electrical system the combination of a low frequency alternating current supply with an electrical transformer having a magnetic core structure upon which are mounted a primary winding and a secondary winding in spaced relation and having a high reluctance magnetic leakage path producing magnetically loose coupling between the primary and secondary coils, and having substantial reactance associated with the secondary winding and having connected across the secondary winding a capacitor resonating the secondary reactance to an harmonic of the low frequency supply and having an arc stabilizing reactance with an electric arc lamp connected to the secondary resonant system.

6. In a pulsating light producing electrical system the combination of a low frequency alternating current supply with an electrical transformer having a magnetic core structure upon which are mounted a primary winding and a secondary winding in spaced relation and having a high reluctance magnetic leakage path producing magnetically loose coupling between the primary and secondary coils, and having substantial reactance associated with the secondary winding and having connected across the secondary winding a capacitor resonating the secondary reactance to an harmonic of the low frequency supply and having an arc stabilizing reactance with an electric discharge lamp connected to the secondary resonant system.

7. In a pulsating light producing electrical system the combination of a low frequency alternating current supply with an electrical transformer having a magnetic core structure upon which are mounted a primary winding and a secondary winding in spaced relation and having a high reluctance magnetic leakage path producing magnetically loose coupling between the primary and secondary coils, and having substantial reactance associated with the secondary winding and having connected across the secondary winding a capacitor resonating the second-

ary reactance to an harmonic of the low frequency supply and having an electric discharge device with an associated stabilizing control connected to the secondary resonant system to receive operating energy therefrom.
